UNITED STATES PATENT OFFICE.

JOSEPH H. COHEN, OF BRIDGEPORT, CONNECTICUT.

WIRE REEL.

Application filed December 4, 1926. Serial No. 152,685.

This invention relates to wire reel arrangements for cigar-lighters, trouble lamps, etc., and particularly those adapted for use on the instrument board of motor vehicles.

5 An object of this invention is to provide simple and positive means for back-checking the operation of a spring-wound cable-carrying reel of cigar-lighters, trouble lamps, etc., so that when desired a cigar-lighter or trouble lamp, which is attached to the end of the cable wound on the reel, may be held automatically in position withdrawn from the reel casing.

10 Other objects and advantages will hereinafter appear.

In the accompanying drawing, showing the preferred form of the present invention—

Figure 1 is a side view of a cable-carrying reel showing it mounted on an instrument board of a motor vehicle.

Fig. 2 is a front elevation of the device shown in Fig. 1.

Fig. 3 is a longitudinal section showing 25 the operating parts of the present invention.

Fig. 4 is a transverse section of the reel and reel casing.

Fig. 5 is a detail view showing the back-check pawl in operative position.

30 As shown in the accompanying drawing, the device of the present invention comprises a reel casing 10 having secured to it an attaching sleeve 11 adapted to pass through an aperture 12 in an instrument board 13 to be clamped thereon by means of a clamping nut 14. The sleeve 11 is adapted normally to receive and hold a nozzle 15 which may contain at its end a cigar-lighting unit 16, or, if desired, a 35 trouble lamp or other electrical appliance, it being old in the art to substitute cigar-lighter units for trouble lamps, etc.

The nozzle 15 is connected to a cable 17 which is wound on a reel 18 comprising a 40 core 19 and side disks 20 and 21. The core 19 is mounted on a bushing 22 rotatably mounted on a rod 23 which is anchored against rotation in the reel casing 10 by a lock nut 24. The disk 21 is provided with 45 a flange 25 containing a winding spring 26 whose one end is fastened to the flange 25 while the other end is fastened to a hook 27 on the shaft 23. As shown in Fig. 4, the wires of the cable 17 are respectively connected to the disks 20 and 21, the former being insulated from the bushing 22 and re-

ceiving current through a brush 28 from a wire adapted to be connected to a binding post 29. The disk 21 is electrically connected to the bushing 22 and through the 60 shaft 23 to the casing 24 and through the casing to the ground of the motor vehicle in case the instrument board is made of metal. In case the instrument board is made of wood as shown in the drawing, a 65 ground wire of the motor vehicle is attached to the shaft 22 by means of a nut 30. By this means, current is carried to the current-consuming device 16 when a switch button 31 on the latter is operated.

70 It frequently occurs, especially when the nozzle 15 is connected to a trouble lamp, that the user desires to keep the nozzle 15 in some position removed from the sleeve 11, as, for instance, under the car when making repairs or adjustments or near one of the wheels when changing a tire at night and, therefore, means have been provided for preventing re-winding movement of the 75 reel 19 when desired.

80 According to the present invention, this is accomplished by providing one or more ledges or abutments 32 on the flange 25 of the disk 21 constituting the reel and a back-check pawl 33 which may cooperate with the 85 ledges 32 to prevent backward movement of the reel. Preferably, this back-check pawl 33 is in the form of a cylindrical block and has one portion of its top cut off to constitute a tooth 34 adapted to engage the ledges 32 and prevent backward movement of the 90 reel. The cylindrical block constituting the back-check pawl 33 is preferably mounted for longitudinal movement in a cylindrical tubular extension 35 riveted or otherwise secured at 36 to the bottom of the casing 10, and the back-check pawl 33 is normally urged upwardly into position to cause the 95 tooth 34 to engage the ledges 32 on the reel by means of a coil spring 37 located in the extension 35 between the end wall 38 thereof and the bottom of the back-check pawl 33.

100 In order that the back-check pawl may be controlled by the operator so that it may be moved to inoperative position when desired 105 and may be held in inoperative position without the attention of the operator, there is provided a control device 39 comprising a flat plate having a narrow finger 40 normally riding in a slot in the cylindrical 110 tubular casing 35 and extending through a slot 42 in the back-check pawl 33. This

slot 42 is sufficiently wide to permit rise and fall movements of the back-check pawl 33 with respect to the finger 40 as the ledges 32 press over the top of the tooth 34 on the 5 back-check pawl 33 during the unwinding movement of the reel (see Fig. 5). The finger 40, by extending through slots in the tubular extension 35 as well as through the slot 40 in the back-check pawl, prevents the 10 back-check pawl from turning and holds the tooth 34 in position to engage the ledges 32 on the reel.

To positively move the back-check pawl 33 out of operative position, the control device 39 is provided with a cam 43 and an extended surface 44, so that when the control device 39 is moved rearwardly or to the left as seen in Fig. 5, the cam 43 will engage the back-check pawl 33 and depress it against the tension of the spring 37, and the continued backward movement of the control device 39 will cause the back-check pawl 33 to be held in depressed position because of the engagement of the flat surface 44 with the 25 flat bottom wall of the slot 42 in the back-check pawl (see Fig. 3). The upward pressure of the back-check pawl 33 against the flat surface 44 of the control device 39, which pressure is caused by the spring 37, is sufficient to hold the control device 39 in adjusted position against accidental withdrawal, and likewise the cam 43 on the control device 39 holds the control device in the 30 position in which it permits the pawl 33 to function, that is to say, in the position shown in Fig. 5.

Of course, the control device 39 may be operated in any desired manner, but, according to the present invention, it is preferable 40 that the forward end on the control device be provided with a screw-threaded portion 46, adapted to be threaded in a rod 47 having a finger-piece 48. This rod 47 preferably has provided for it a bushing 49 which passes 45 through a hole 50 in the instrument board, behind which it is in screw-thread engagement with a supporting arm 51 secured to the reel casing 10.

In assembling the device on the instrument 50 board after the suitable holes 12 and 50 have been provided therein, the sleeve 11 is passed through the holes 12 and the device is secured in place by the nut 14 after the sleeve 49 and the operating rod 47 are removed 55 from the arm 51. After this is done, the sleeve 49 and the rod 47 are screwed back in place on the supporting arm 51 and the screw-threaded portion 46 of the control device 39.

The control device 39 is so shaped that it 60 has a forward stopping shoulder 52 adapted to engage the arm 51 when the handle 48 is pulled outwardly, and a shoulder 53 which is adapted to engage the extension 35 when 65 the handle 47 is pushed inwardly, thus the

two positions of the control device 39 are accurately determined without adding any extra parts for the purpose.

Variations and modifications may be made 70 within the scope of this invention and portions of the improvements may be used without others.

Having thus described the invention, what is claimed as new and for which it is desired 75 to obtain Letters Patent, is:—

1. In combination, a reel casing; a wire reel mounted therein; a spring for said reel; a tubular extension in said reel casing; a back-check pawl for said reel mounted in 80 said tubular extension; a spring mounted in said tubular extension between the back-check pawl and the end wall of said extension and tending to urge said back-check pawl toward said reel and a cam acting on said pawl to move the same to inoperative 85 position against the tension of said spring.

2. In combination, a reel casing; a wire reel mounted therein; a spring for said reel; a tubular extension in said reel casing; a back-check pawl for said reel mounted in 90 said tubular extension; a spring tending to urge said back-check pawl outwardly of said tubular extension toward said reel; and a control device guided in said extension for movement therethrough transversely of the 95 extension for positively withdrawing said back-check pawl against the tendency of said spring away from the reel into inoperative position.

3. In combination, a reel casing; a wire 100 reel mounted therein; a spring for said reel; a tubular extension in said reel casing; a back-check pawl for said reel mounted in 105 said tubular extension; a spring mounted in said tubular extension between the back-check pawl and the end wall of said extension and tending to urge said back-check pawl toward said reel; and a control device guided in said extension for movement 110 therethrough transversely of the extension for positively withdrawing the back-check pawl against the tendency of said spring away from the reel into inoperative position, 115 said spring when tensioned by movement of the back-check pawl to inoperative position being adapted to yieldingly hold said control device, through the engagement of the back-check pawl therewith, against accidental movement.

4. In combination, a reel casing; a wire 120 reel mounted therein; a spring for said reel; a circular tubular extension in said reel casing; a cylindrical back-check pawl for 125 said reel mounted in said tubular extension and having at one end a tooth for cooperation with a stopping ledge on said reel; and a control device comprising a flat strip extending through and beyond said cylindrical tubular extension and through a slot in said cylindrical back-check pawl to operate the 130

back-check pawl to move the same from operative to inoperative positions and to prevent rotation of the cylindrical back-check pawl in the cylindrical casing, so that the 5 tooth on the cylindrical back-check pawl will be maintained in proper operating position.

5. In combination, a reel casing; a wire reel mounted in the casing; a spring for said reel; a back-check device for said reel; an 10 arm secured to said casing and extending beyond the same; a sleeve mounted in said

arm and adapted to extend through an instrument board of a motor vehicle; and manually operable means for controlling said back-check device, said manually operable 15 means being slidably mounted in said sleeve for operating movements.

Signed at Bridgeport, in the county of Fairfield, and State of Connecticut, this 19th day of November, 1926.

JOSEPH H. COHEN.
